MUD FEEDER FOR OIL WELLS

Hubert W. Hudspeth, Hobbs, N. Mex.

Application July 22, 1952, Serial No. 300,148

4 Claims. (Cl. 302—15)

This invention relates to a mud feeder for oil wells. In the drilling of oil wells, mud is fed to the well so as to provide a means for removing the drilled-out material. An object of this invention is to provide an improved means for regulating the discharge of dry mud into a water pipe.

Another object of this invention is to provide a mud regulator which can be mounted in conventional hoppers and which will correctly meter the mud discharged from the hopper, and will permit the hopper to be substantially filled with dry mud at one operation and thereby eliminate the need for a constant attendant to feed the mud slowly to prevent clogging.

A further object of this invention is to provide an improved mud feeding device which includes means for admitting metered quantities of air to the mud valve so as to assure an even flow of mud.

With the above and other objects in view, my invention consists in the arrangement, combination and details of construction disclosed in the drawings and specification, and then more particularly pointed out in the appended claims.

In the drawings:

Figure 1 is a detail side elevation, partly in vertical section, of a feeder for a mud hopper constructed according to an embodiment of this invention.

Figure 2 is a sectional view taken on the line 2—2 of Figure 1.

Figure 3 is a fragmentary sectional view taken on the line 3—3 of Figure 2.

Figure 4 is a plan view, partly in section, of the air feeder.

Figure 5 is a fragmentary sectional view taken on the line 5—5 of Figure 2.

Figure 6 is a sectional view taken on the line 6—6 of Figure 3.

Referring to the drawings, the numeral 10 designates generally an elongated tubular housing which is formed of a tubular upper member 11 connected to a tubular lower member 12 by means of a cylindrical coupling member 13. The lower tubular member 12 is formed with a reduced diameter lower end 14 which is threaded into a cylindrical sleeve 15.

The sleeve 15 snugly fits within a cylindrical discharge nipple 16 carried by the lower end of an upwardly flared or substantially conical hopper 17. The nipple 16 of the hopper 17 is mounted within an upstanding coupling nipple 18 carried by a horizontal water conducting pipe 19. The water pipe 19 is formed adjacent the lower end of the hopper 17 with a reduced diameter pipe 20 which forms a nozzle and venturi whereby water under pressure will flow to the left, as viewed in Figure 1, and will thereby form a suction for drawing downwardly into the pipe 19 dry mud which is discharged into the hopper 17.

The lower housing member 12 is provided with a plurality of vertical elongated intake ports 21 which are arranged circumferentially about the housing member 12

2

and a cylindrical valve member 22 is slidable within the housing member 12. The valve member 22 is adapted to be vertically moved as will be hereinafter described so as to regulate the opening or closing of the intake ports 21. These ports 21 are disposed adjacent the lower small end of the hopper 17 so that the dry mud within the hopper may gravitantly flow through the ports 21 into the housing member 12.

A horizontally disposed shaft 23 is journaled diametrically across the upper housing member 11 and has secured within the housing member 11 a substantially T fitting 24 which includes an arm 25 extending at right angles to the shaft 23. A connecting link 26 is secured at its upper end to the arm 25 and is secured at its lower end to a diametrically disposed bar 27 which is secured within the upper portion of the valve member 22.

The shaft 23 has an inner spring 28 engaging therewith which bears against the housing 11 and fitting 24 and a second or outer spring 29 bears at its inner end against the outer side of the housing member 11 and bears at its outer end against a nut or spring tensioning member 30 mounted on the adjacent outer end of the shaft 23. An L-shaped coupling 31 is secured to the opposite end of the shaft 23 and an elongated handle or crank arm 32 is secured to the L 31 and extends upwardly therefrom. The springs 28 and 29 yieldably hold crank arm or handle 32 against a notched keeper bar 33 (Fig. 4) which is fixed to the outer side of the housing member 11. The keeper bar 33 is formed adjacent the opposite ends thereof with stop members 34 which limit the rocking movement of the handle 32. A cap 35 is threaded onto the upper end of the upper housing member 11 and is formed with a top wall 36 having a pair of sector-shaped openings 37 which are diametrically disposed.

35 A valve plate 38 is pivotally mounted on a pivot 39 and is movable relative to the openings 37 so as to open or close the openings for admission of air through the upper end of the upper housing member 11. A handle 39a extends from the valve member 38 so that this valve member can be readily adjusted to provide for opening or closing of the openings 37.

In the use and operation of this device, the feeder hereinbefore described is firmly set into the hopper nipple 16 and extends vertically and axially upwardly through the hopper 17. The dry mud is then discharged into the hopper 17 and valve member 22 is vertically adjusted to provide for the desired flow of the dry mud into the mixing pipe 19. The force of the water flowing horizontally from the nozzle pipe 20 into the mixing pipe 19 will cause the dry mud to be drawn downwardly into the mixing pipe 19. The rate of flow of the dry mud is controlled by vertical adjustment of the valve member 22 and the adjustment of the air valve member 38.

55 With a feeder as hereinbefore described, the hopper 17 may be initially completely filled with the dry mud and it will be unnecessary for an attendant to constantly watch the condition of the hopper after the valve members 22 and 38 have been initially set. As a matter of practice 60 the mud is discharged from one hundred pound bags into the hopper 17 and with the use of conventional hopper devices not containing valved suction devices it is necessary for one or more attendants to be constantly watching the flow of the mud so that the mud will move downwardly into the mixing pipe or chamber 19. However, with the device hereinbefore described, the device will operate without constant attendance of the operator and the mud will evenly flow downwardly for mixing with the water discharged from the nozzle pipe 20 into the mixing pipe or chamber 19.

65 I do not mean to confine myself to the exact details of

construction herein disclosed, but claim all variations falling within the purview of the appended claims.

What I claim is:

1. A feeder for mud hoppers including a discharge nipple and a water actuated suction means below said nipple, said feeder comprising a vertically disposed tubular housing adapted for mounting in said nipple, said housing having a plurality of intake ports adjacent the lower portion thereof, a cylindrical valve slidable in said housing, means, including a valve actuating link connected with said valve for adjusting the latter relative to said ports, said link being disposed in said housing, and adjustable valve means at the upper end of said housing for regulating the entrance of air into said housing to vary the degree of suction.

2. In combination a hopper for receiving dry mud, a water pipe connected with the lower end of said hopper and extending at right angles relative to said hopper, a tubular upright housing fixed at its lower end in said hopper, said housing having intake ports in the lower portion thereof, a cylindrical valve slidable in said housing, means carried by the upper portion of said housing connected with said valve for adjusting said valve relative to said ports, said means including a valve actuating link disposed in said housing, and valve means for admitting air into the upper end of said housing, the relative position of said cylindrical valve and said valve means determining the degree of suction at the lower end of said hopper.

3. In combination a hopper for receiving dry mud said hopper having a discharge nipple, a water pipe connected with the lower end of said nipple and extending at right angles relative to said hopper, a tubular upright housing fixed at its lower end in said nipple, said housing having intake ports in the lower portion thereof, a cylindrical valve slidable in said housing, a shaft journaled diametrically across the upper portion of said housing, an arm fixed to said shaft in said housing, a link connecting said arm with said valve, a right angularly disposed handle fixed to the outer end of said shaft, and means holding said lever in angularly adjusted position, and a valve controlling the quantity of air admitted into the upper end

of said housing to vary the degree of suction in accordance with the position of the cylindrical valve, said last-named valve comprising a closure member for the upper end of said housing and provided with a plurality of apertures, and a disk pivotally mounted on said closure member, said disk being adjustable relative to said apertures to control the flow of air through said tubular housing.

4. A feeder adapted for mounting in a mud hopper comprising a tubular upright housing fixed at its lower end in said hopper, said housing having a plurality of intake ports in the lower portion thereof, a cylindrical regulating valve slidable in said housing, a shaft journaled through said housing adjacent the upper portion thereof, a right angular arm fixed relative to said shaft within said housing, a link pivotally connected to said arm and said valve whereby rocking of said shaft will adjust said valve relative to said ports, inner and outer springs on said shaft yieldably holding the latter against endwise movement, a right angularly disposed handle fixed to one end of said shaft, a notched keeper element fixed to said housing and engageable by said handle for holding the latter in angularly adjusted position, and adjustable valve means at the upper end of said housing for regulating the admission of air through the upper end of said housing, the relative position of said cylindrical regulating valve and said adjustable valve means controlling the degree of suction, said last-named valve comprising a closure member having a plurality of sector-shaped openings extending transversely therethrough, said closure member being mounted on the upper end of said housing, and a disk pivotally connected on said closure member and adjustable relative to said sector-shaped openings to control the flow of air through said tubular housing.
